FABRICATED METAL IRONING BOARD TOP

Filed April 4, 1945

UNITED STATES PATENT OFFICE

2,487,762

FABRICATED METAL IRONING BOARD TOP

Quintin G. Noblitt and Earl C. Booth, Columbus,
Ind., assignors to Noblitt Sparks Industries,
Inc., Columbus, Ind., a corporation of Indiana

Application April 4, 1945, Serial No. 586,492

6 Claims. (Cl. 38—137)

1

Our invention relates to ironing boards and more particularly to an ironing-board top. It is the primary object of our invention to provide an ironing-board top which will lend itself to construction from metal tubing and sheet-metal stampings. Other objects of our invention are to provide an ironing board top which can be simply and economically manufactured, to provide a top which will be strong and rigid, and to make a top which will be light in weight.

In carrying out our invention, we provide for the top a border frame conveniently formed of metal tubing. Such border frame is completely covered by a series of sheet-metal stampings which extend transversely of the border frame and are secured to the sides thereof. To stiffen the panels and the top as a whole, each panel is provided along its sides and across its ends with depending flanges which are relatively narrow over the sides of the border frame and relatively wide between the border-frame sides. The relatively wide portions of the peripheral flanges of adjacent stampings are disposed in contact with each other and secured together as by spot welding. To receive the narrow portions of the peripheral flanges at the sides of the panels, the metal of the border frame is offset inwardly so that the body of each panel may lie against and be spot-welded to the tubular border frame.

The accompanying drawing illustrates our invention: Fig. 1 is a side elevation of an ironing board in extended condition; Fig. 2 is a plan view of the top with one panel in position thereon; Fig. 3 is a longitudinal vertical section on the line 3—3 of Fig. 2; Fig. 4 is a transverse vertical section on the line 4—4 of Fig. 2; Fig. 5 is a fragmental section on an enlarged scale on the line 5—5 of Fig. 7; Fig. 6 is a fragmental plan view similar to Fig. 2 but on an enlarged scale; and Fig. 7 is a fragmental vertical section on the line 7—7 of Fig. 6.

The top shown in the drawing comprises a border frame 10 of metal tubing extending completely around and defining the periphery of the top. Extending across the border frame at a point intermediate its length we provide a cross member 11 conveniently formed as a sheet-metal stamping having at its ends down-turned flanges 12 which fit against and are welded to the sides of the border frame. To increase the rigidity of the cross member 11 and the rigidity of the top as a whole we depress the center portion 13 of the cross member and turn its edges upwardly to form flanges 14. Desirably, the undepressed end portions 15 of the cross member 11 and the

upper edges of the flanges 14 are substantially flush with each other and with the upper surface of the border frame, as will be clear from Fig. 4.

Extending from one end of the border frame 5 to the other we provide a truss-like brace 17 the ends of which are secured to the border frame. Desirably the brace 17 is of metal tubing and its ends are welded to the ends of the border frame. The intermediate portion of the brace 17 is depressed and passes beneath the cross-member 11 to which it is secured. Conveniently, the web 13 of the cross-member is provided with two down-struck ears 18 between which the brace 17 is located and to which it is secured by a rivet or 15 bolt 19.

The frame of the ironing-board top as above described is covered with a series of panels 21, formed as sheet-metal stampings, extending transversely of the border frame. Across each 20 end of the panels 21 is provided a relatively narrow down-turned flange 22, while along each side each panel is provided with relatively wide down-turned flanges 23. At each end, the width of each 25 of the flanges 23 is reduced substantially to the width of the end flanges 22, as will be clear from Fig. 5. Adjacent panels are disposed with their adjacent flanges 23 in contact, and such contacting flanges are desirably secured together as by spot-welding. At appropriate intervals, the wall 30 of the tubing forming the border frame 10 is offset inwardly to provide a transversely extending groove 25 adapted to receive the narrowed portions of the flanges 23. This permits the body of each panel 21 to rest upon and to be spot-welded to the tubing of the border frame. The 35 end flanges 22 of each panel desirably extend downwardly into contact or substantially into contact with the wall of the border-frame tubing in the manner illustrated in Fig. 5.

40 For the purpose of reducing the weight of the ironing-board top, each of the panels 21 may be provided with a multiplicity of perforations 27.

In addition to the ears 18, the cross-member 11 may be provided with additional down-struck 45 ears or flanges 30 through the medium of which the top may be connected to the legs 31 and 32 of a collapsible supporting structure. The particular supporting structure illustrated in Fig. 1 is that more fully illustrated and described in the 50 copending application of Frank Jones and Earl C. Booth, Serial No. 586,466, filed April 4, 1945, now Patent No. 2,469,809, dated May 10, 1949. Such supporting structure forms no part of our 55 present invention, and other supporting structures may be substituted therefor if desired.

We claim as our invention:

1. An ironing-board top, comprising an elongated border frame formed of metal tubing, a plurality of sheet-metal panels extending transversely between and resting on and secured to the sides of said border frame, adjacent panels being provided with abutting, generally vertical flanges extending transversely of the top and welded together, said flanges extending over the sides of the border frame and being of greater depth between the sides of the border frame than above such sides, the tubing of the border frame beneath abutting flanges being indented to receive the flanges and permit the body of each panel between its flanges to rest on such tubing.

2. In an ironing board top, an elongated border frame, and a cross member extending across said frame at a point intermediate its length, said cross member being formed of sheet metal and provided at its ends with flanges abutting and secured to the inner surfaces of the border-frame sides, the intermediate portion of the cross member being vertically offset from horizontal end portions adjacent the border frame sides and the sides of said offset intermediate portion being bent at right angles to form vertical flanges, the edges of said last named flanges extending continuously between said horizontal end portions and being substantially coplanar therewith.

3. In an ironing board top, an elongated border frame, and a cross member extending across said frame, said cross member being formed of sheet metal and being secured at its ends to the border-frame sides, the intermediate portion of the cross member being offset vertically from horizontal end portions adjacent the border-frame sides and the sides of said offset intermediate portion being bent at right angles to form vertical flanges, the edges of said flanges extending continuously between said horizontal end portions and being substantially coplanar therewith.

4. The invention set forth in claim 3 with the addition that the intermediate portion of the cross member is offset downwardly, the edges of said flanges and the end portions of the cross member being substantially coplanar with the upper surface of the border frame.

5. The invention set forth in claim 3 with the addition that said cross member is provided with down-struck ears adapted for attachment to a collapsible top-supporting structure.

6. The invention set forth in claim 3 with the addition of a brace extending between and secured to the ends of said border frame and passing beneath said cross member, said cross member being provided with down-struck ears which are located on opposite sides of said brace and to which the brace is secured.

QUINTIN G. NOBLITT.
EARL C. BOOTH.
